UNITED STATES PATENT OFFICE

BENJAMIN L. FRY, OF ST. LOUIS, MISSOURI

COIN-CONTROLLED MECHANISM

Application filed August 13, 1930. Serial No. 475,042.

This invention relates to coin-controlled vending machines of that type in which packages of goods to be sold are arranged in columns of superposed compartments and a closure common to all the compartments is given a step by step movement to successively expose the goods in the compartments for delivery. The object of the present invention is to provide simple and compact means for effecting the desired step by step movement of the door or closure and to permit a return movement of the door or closure to its initial position after restocking of the compartments. The invention is illustrated in the accompanying drawings and will be herein-after first fully described and then more particularly defined in the appended claims.

In the accompanying drawings:

Figure 1 is a front elevation, partly broken away, of a portion of a column of compartments embodying the invention, the cabinet in which the compartments are housed being omitted,

Fig. 2 is a horizontal section on the line 2—2 of Fig. 1,

Fig. 3 is a vertical section on the line 3—3 of Fig. 1,

Fig. 4 is a vertical section on the line 4—4 of Fig. 3,

Figs. 5 and 6 are detail views illustrating different positions of the pocket wheel which is actuated by an inserted coin, and

Fig. 7 is a detail perspective view of the pocket wheel.

Referring to the drawings, the numeral 1 indicates side plates of a vertical column which are preferably of sheet metal and between which shelves 2 are secured to divide the column into a series of superposed compartments, the column of compartments being housed within a cabinet, a portion of which is indicated at 3. Near the front edges of the side plates 1, I secure thereto on their inner sides reinforcing strips or bars 4 which extend the full height of the column, and a closure or door 5 is slidably mounted in advance of said reinforcing bars or strips. The side plates are extended forwardly beyond the strips 4 and are doubled upon themselves to form re-entrant flanges 6, the edges

of the door being disposed between said flanges and the strips 4 so as to be guided thereby. At one side the door or closure 5 is formed with a flange 7 fitting within the adjacent re-entrant flange 6 and in said flange 7 are equi-distant notches 8 which are engaged by the teeth 9 of a feeding wheel 10 mounted in front of the door, as shown in Fig. 2, the re-entrant flange 6 having openings 11 therethrough to accommodate the teeth 9, as will be understood. The wheel 10 is secured on the rear or inner end of a shaft 12 which is journaled in and extends through a casing secured over the front side of the column within the cabinet and including a front plate 13 and side plates 14 extending rearwardly therefrom and riveted or otherwise secured to the side plates 1 of the column. A spacing disk 15 is disposed about the shaft 12 between the wheel 10 and the face plate 13 so as to maintain the wheel 10 in its proper position and also to resist buckling of the face plate and upon the front end of the shaft immediately adjacent the face plate is secured a pocket disk 16. The disk 16 is so arranged that its periphery will be immediately below a coin chute 17, the upper end of which projects through the upper portion of the cabinet, as shown in Fig. 3. The coin chute is illustrated in the present drawings in a more or less conventional manner as it may be of any preferred form and constitutes, in itself, no part of the present invention. It may be stated, however, that in actual practice I employ a coin tube equipped with an ejecting mechanism whereby proper coins will be permitted to pass to the pocket disk and operate the machine while slugs or other spurious devices which may be inserted will be ejected and prevented from passing to the operating mechanism. The disk 16 is formed with a plurality of pockets 18 on its rear face and immediately adjacent each pocket in the periphery of the disk is a shoulder 19 which is adapted to be engaged by a pawl 20 pivoted upon the face plate 13 and held normally to the disk by a retractile spring 21 attached to the pawl and to the face plate, as clearly shown in Fig. 1.

The face plate 13 is provided with a notch

22 in its upper edge and on the inner side of the face plate is mounted a dog 23 which has its lower end below its pivot formed into a tooth 24 adapted to engage in one of the 5 openings 8 in the flange of the door or closure 5. To the upper end of the dog 23 is pivoted a latch 25 which normally rests on the upper edge of the face plate 13 and is provided with a terminal lug 26 adapted at times to seat 10 in the notch 22 to thereby hold the dog out of engagement with the door or closure 5.

10 The door is provided near its upper end with a lifting lug or finger-hold 27 whereby it may be raised to its initial position.

15 Upon reference to the drawings, more particularly Fig. 4, it will be noted that the weight of the door 25 is carried by the teeth 9 of the wheel 10 and consequently there is a constant tendency of the door to descend by 20 the force of gravity. This tendency, however, is resisted by the pawl 20 which engages the stop shoulders 19 on the disk 16 inasmuch as said disk is secured to the shaft 12 to which the wheel 10 is also secured. When 25 a coin, indicated at 27', is inserted, it passes at once to the periphery of the disk 16 and partly enters the uppermost pocket 18, as shown in Fig. 1, coming to rest upon the edge of the pocket and against the end of the pawl 20.

30 If the door 5 be now given a slight upward movement, the wheel 10 and consequently the disk 16 will be rotated just enough to permit the coin to drop fully into the pocket, as shown in Fig. 5, and this movement of the 35 coin will carry it partly under the end of the pawl so that if the finger-hold upon the door 5 be released the weight of the door will carry it downwardly and the wheel 10 will be rotated, the rotation being transmitted 40 through the shaft 12 to the disk 16 and the coin being carried under and past the pawl to permit the free end of the pawl to again drop onto the periphery of the disk, as shown in Fig. 6. The rotation of the wheel 10 and 45 the disk 16 will continue until a succeeding stop shoulder 19 on the disk is brought against the end of the pawl, whereupon the parts will be held at rest in the position shown in Fig. 1. The distances between successive 50 shoulders 19 on the disk 16 will correspond to the heights of the compartments in the column so that each operation of the disk and wheel will permit door 5 to descend and fully uncover the end of one compartment and only 55 one compartment. Any attempt to juggle the movements of the door by manipulation of the same to impart retrograde movement thereto and thereby possibly free the door for uncovering two compartments will be frustrated by the engagement of the dog 23 with the notches 8 of the door, the point 24 of the dog passing through an opening 28 in the flange 6 to engage the notches 8 of the closure, as 60 shown clearly in Fig. 4. When all of the 65 compartments have been exposed and restock-

ing of the same is desired, the fresh merchandise may be inserted in the compartments through the exposed free ends of the same but to permit the closure to be returned to its initial position, the operator must unlock the 70 cabinet and disengage the dog 23 from the closure. This disengagement is effected by merely releasing the dog and engaging the latch 25 in the notch 22 so that the dog will be held from the flange 7 of the closure. 75 Then by gripping the flange or finger-hold 27, the door may be raised to its initial position, the shoulders 19 of the pocket disk 16 riding under the pawl 20 in an obvious manner.

80 The mechanism of the present invention is exceedingly simple and compact and may be very readily produced and installed at a low cost. It will be noted that the toothed wheel and the pocket disk as well as the parts co-operating therewith are all carried by the 85 face plate 13, and the casing consisting of said face plate and the side plates 14 may be assembled with the moving elements and then secured over the front of the column within the cabinet. The very few parts necessary to 90 produce the mechanism makes for economy in construction and minimizes the liability of the mechanism to get out of order and need attention.

Having thus described the invention, I 95 claim:

1. In a vending machine including a column of compartments and a vertically movable closure common to all the compartments, an escapement wheel engaged with the closure and adapted to be rotated by the weight of the closure, a pocket disk connected with said escapement wheel to rotate therewith and arranged to receive a deposited coin when 100 partly rotated by a slight lifting of the closure, and means engaged with the disk to prevent rotation of the same and the escapement wheel, the last-mentioned means being arranged to be engaged and released by a 105 coin received and held in a pocket of the disk. 110

2. In a vending machine including a column of compartments and a vertically movable closure common to all the compartments, the combination of an escapement wheel engaged with the closure and adapted to be 115 operated by the weight thereof, a disk having a series of peripheral pockets and stop shoulders arranged adjacent the respective pockets, and a pawl adapted to engage the stop shoulders and thereby hold the disk and the escapement wheel against rotation, the pockets being adapted to receive a coin and initially support the same against the pawl whereby a slight lifting of the closure will 120 effect a partial rotation of the disk in one direction permitting the coin to fully enter a pocket whereupon reversal of the movement of the disk will free the pawl and permit rotation of the disk and the escapement wheel 125 and descent of the closure. 130

3. In a vending machine including a column of compartments and a vertically movable closure common to all the compartments, the combination of a flange on the closure having equi-distant openings therein, an escapement wheel mounted adjacent the closure and adapted to engage the openings in said flange, a disk mounted coaxially with the escapement wheel and connected therewith, said disk having peripheral stop shoulders and being provided on one side with shallow pockets each having one terminal adjacent a stop shoulder and at its opposite terminal flared away from the stop shoulder, and a pawl mounted adjacent the disk and having its free end riding on the periphery of the disk whereby a coin may be momentarily arrested by the end of the pawl and the abrupt side of the pocket, whereby a slight lifting of the closure will effect a partial movement of the disk in one direction permitting the coin to fully enter the pocket and a reverse movement of the disk causing the coin to ride under and release the pawl.
4. In a vending machine including a column of compartments and a vertically movable closure common to all said compartments, coin-controlled means for effecting a step by step descent of the closure, a dog mounted adjacent the closure to engage the same and prevent upward movement thereof, a support for said dog having a notch in its upper portion, and a latch pivoted to the dog and adapted to seat in said notch to release the dog and permit upward movement of the closure.

In testimony whereof I affix my signature.
